(74) Attorney, Agent, or Firm — Charles F. Meroni, Jr.;
Meroni & Meroni, PC(57) **CLAIM**

The ornamental design for the ring bottle opener, as shown and described.

DESCRIPTION

FIG. 1 is a front perspective view of the ring bottle opener according to the present invention.

FIG. 2 is a top view of the ring bottle opener.

FIG. 3 is a side view thereof.

FIG. 4 is a sectional view of FIG. 3 taken along the line 4-4.

FIG. 5 is an enlarged detail view of a portion of FIG. 4.

FIG. 6 is a sectional view taken along the lines 6-6 in FIG. 2; and,

FIG. 7 is an enlarged sectional view of a portion of FIG. 6 taken along the line 7-7.

1 Claim, 4 Drawing Sheets(56)
